ALARM FOR DEAF PERSONS

Pasquale Rody, Philadelphia, Pa.

Application May 14, 1948, Serial No. 27,004

I Claim. (Cl. 161-22)

This invention relates to an alarm in connection with a time piece, and more particularly to an alarm adapted for use of deaf persons to arouse them from sleep.

An object of this invention is to provide an alarm whereby unheard vibrations rather than sound may be used to arouse a person.

Another object is to provide means whereby an electrically-driven clock will set such an alarm, remotely located, into action.

A further object is to provide means whereby such an alarm may be supported on and transmit vibrations to the frame of a bed or other suitable furniture.

A further object is to provide an electric alarm device having an operating member resonant to the frequency of the actuating current or to multiples of sub-multiples thereof.

Still further objects and advantages reside in the combination and arrangement of parts, as will be hereinafter more fully described and readily understood by reference to the accompanying drawings in which:

Figure 1 is an elevational view showing the main features of the invention.

Figure 2 is an elevational front view of the timepiece or clock.

Figure 3 is an elevational rear view of the clock.

Figure 3 is an elevational rear view of the clock. Figure 4 is a front elevation of the alarm device.

Figure 4 is a front elevation of the alarm device. Figure 5 is a side elevation of the alarm device.

As shown in Figure 1, an electric clock 10, having contacts adapted to close an electrical circuit at a predetermined time, is connected to a source of current 11 by means of conducting cord 12, and to the alarm device generally designated as 13 by means of a conducting cord 14. The alarm device 13 is secured to the frame 15 of a bed 16 in such manner that vibrations produced by the alarm device will be conveyed by means of the bed frame 15 to the sleeper in the bed.

In Figure 2 is shown, in front elevation, the clock 10 provided with an off-on switch 11, an alarm setting knob 18, and alarm time-indicating hand 19.

On the rear of the clock 10 is shown, in Figure 3, a socket 19a connected to the alarm contacts within the clock into which the plug of conducting cord 14 may be inserted.

The alarm device 13 consists, as shown in Figures 4, 5 and 6, of an electromagnet coil 20 with casing or cover 20a, supported on a magnetic core 21 having a pair of perpendicularly disposed arms or pole pieces 22 and 23 which are also used to support the insulated terminal posts 24 and 25 of the coil conductor.

Pole-piece **23** is slightly higher than pole-piece **22** and one end of a vibrational armature **26** is secured at one end to pole piece **23** by means of screws or rivets **28** and its free end is provided with a hammer **29**. An armature spring **26a**, secured at one end to armature **26** by riveting or otherwise, is attracted to pole-piece **22** when alternating or pulsating current is supplied to the magnet coil **20** and thus vibrates the armature **26** causing the hammer **29** to strike the bed post **15**. The vibrations of the bed-post are then conveyed to the person in the bed.

Armature spring **26a** and armature **26** may be so proportioned in size and weight as to respond 15 to the frequency of the applied current or to multiples or sub-multiples thereof and thus render a resonant or harmonic response with respect to the frequency of the actuating current. If it is desired to use direct current the armature 20 spring **26a** may be provided with electrical make and break contacts (not shown) in the usual manner such as is used, for example, in an electric bell operated by batteries.

A non-magnetic supporting bracket 29, secured in any suitable manner to pole-pieces 22 and 23, may be used to attach the alarm device 13 to a bed or other furniture by means of screws 24.

24. It will be understood that when the plug of conductor 12 is inserted in the receptacle 11 and the plug of conductor 14 is inserted in socket 19a on the back of the clock 10, the necessary current will be supplied to operate the clock, and the alarm device 13 will also be operated whenever 30 its circuit, which is connected to the main circuit in the clock, is closed by the contacts in the clock at the hour set by means of knob 18 provided off- 35 on switch 17 is set in the proper position.

It will also be understood that various modifications and changes may be made in this invention without departing from the spirit and scope thereof, as set forth in the appended claim.

What is claimed is:

45 An alarm device comprising a vertically disposed electromagnet adapted to be positioned below and spaced from the rail of a bed and fixedly secured thereto, a vertically disposed armature positioned on one side of said bed rail and connected to said electromagnet for vibratory movement toward and away from said bed rail, a hammer projecting transversely of said armature adjacent the upper end thereof and engageable with said bed rail upon vibratory movement of said armature toward said bed rail, an alarm 50 clock including a time switch, and circuit-connecting means connected between said time

switch and said electromagnet for actuating said armature and said hammer at a selected time determined by said time switch.
